UNITED STATES PATENT OFFICE

2,486,704

ADJUSTABLE SHOE HEEL

Harry Cameron, Jersey City, N. J.

Application November 28, 1945, Serial No. 631,305

3 Claims. (Cl. 36—36)

1

My invention relates to footwear and more particularly to a heel construction including a rotatably mounted disk comprising a lower rear portion of the heel.

A primary object of this invention is to provide means whereby a heel can be reconditioned to overcome unequal wear frequently occurring at the rear portion of a heel.

Another object of this invention is to provide a heel construction in which a rotatable disk in the lower rear portion of the heel can be easily replaced, after the same has been rotatably adjusted one or more times. In other words, the disk is bodily removable so as to facilitate reconditioning of the heel by replacement of the disk, as well as by rotation of the disk.

Other features and advantages will become more readily apparent from a consideration of the following description and the accompanying illustrative drawings in which:

Figure 1 is a fragmentary elevational view of a shoe embracing my invention;

Figure 2 is a bottom plan view of the structure shown in Figure 1, with the rotatable disk removed;

Figure 3 is a longitudinal vertical sectional view of the structure shown in Figure 1, the parts hereinafter referred to as the thimbles being shown in elevation;

Figures 4 and 5 are lower plan views of the heel; Figure 4 being designed to indicate the position of a worn portion of the rotatable disk before adjustment, and Figure 5 indicating a possible location of the worn portion after adjustment;

Figure 6 is an enlarged fragmentary vertical sectional view of the above mentioned thimble, attaching screw used therein, a portion of a part hereinafter referred to as the ring, and contiguous portions of the heel;

Figures 7 and 8 represent the abovementioned thimble, in perspective and in vertical section, respectively, the thimble being shown in a form assumed before the split heads thereof are expanded into the positions indicated in Figure 6;

Figure 9 is a three dimensional view of the above mentioned ring and a small center disk, both of which members are embedded in the rotatable disk.

In the above drawings, as well as in the specification to follow, the same characters of reference indicate the same parts throughout.

Heels become worn unequally at the rear edges, depending upon the particular wearer and his

2

manner of walking. Such wear, especially if pronounced, has a tendency to throw the wearer off balance and in an effort, usually unconscious, to overcome this condition the wearer may be subject to fatigue, resulting in nervous strain, depleting the natural energy and often-times resulting also in irritability, the cause of which is usually unrecognized. With a view to overcoming these difficulties, I have designed the shoe heel illustrated in the accompanying drawings, the heel being embodied in a shoe generally indicated at 10, and the insole 12 and outsole 14 need not be materially altered by this invention. However, the heel generally indicated by the numeral 16 is of novel construction and will be described in detail.

The heel 16 is comprised of three main portions, the heel lift 18, the fixed top lift portion 20 and the remaining portion of the top lift which 20 will be referred to hereinafter as the rotatable disk 22. It is proposed that this disk 22 will ordinarily be constructed of resilient material such as compound rubber, although this invention may be implemented by the use of rotatable 25 disks of other materials, including leather, and the same consideration with regard to the composition of the elements 18 and 20 will apply. The fixed top lift portion 20 is recessed at the rear side thereof as indicated at 24, the shape of 30 this recess being preferably substantially semi-circular so that the forward one-half portion of the rotatable disk 22 will fit into this recess, it being understood that the fixed heel portion 20 and the rotatable disk 22 will have the same 35 thickness and that the width of the fixed top lift portion will be substantially equal to the diameter of the rotatable disk.

The heel lift 18 has a plurality of thimbles 26 fixed therein, and arranged in regularly spaced 40 relation near the circumference of the disk 22, the drawings representing four such thimbles although the number thereof is a matter of individual preference and mechanical expediency. Each of these thimbles 26 is generally cylindrical 45 with a threaded bore 28 and the ends are split as indicated at 30 in Figure 2 to provide riveting flange portions 32 on the lower ends of the thimbles and substantially similar riveting flange portions 34 on the upper ends of the thimbles, 50 these portions 32 and 34 being expanded by a suitable tool, during the construction of the heel, to fix the thimbles rigidly in the heel lift 18. At 55, in Figures 7 and 8, there is depicted a thimble in the form thereof assumed before the said expansion of the rivet is completed.

A similar thimble 38 is secured in the heel lift 18 coaxially of the disk 22, and screws 40 and 42 are screwed into the thimbles 26 and 38, to hold the disk 22 in position. The rotatable disk 22 is provided with corresponding transverse bores 44 and 46, near the periphery and at the center of the disk, respectively, and a ring 48 and disk 50, ordinarily constructed of metal and of plate character, are embedded in the disk 22 adjacent to the upper surface of the disk 22 and arranged coaxially thereon, the ring 48 and disk 50 serving as reinforcement members and abutments against which the heads of the screws 40 and 42 may be engaged. It should be carefully noted that the screws 42 are inserted through the apertures 52 in the ring 48, while the screw 42 is inserted through the aperture 54 at the center of the disk 50, the other apertures 56 in the ring and 58 in the disk 50 being provided merely to allow the material of the disk 22 to flow thereto thus anchoring the ring and disk 50 firmly within the disk 22.

It will be understood that the necessary nails 60 will be used to secure the heel lift 18 and the fixed top lift portion 20 on the outsole 14. It will be clear how a worn portion indicated at 62 in Figure 4 originally positioned at one side and at the rear of the disk 22 may be moved into the position indicated at 64, by the expedient of loosening the screw 42 and removing the screws 40, rotating the disk 22, as for example through 180 degrees into the second position indicated, replacing the screws 40 and retightening the screw 42. It will also be clear that the disk 22 is easily removable, by merely removing all the screws 40 and the screw 42, allowing a replacement disk 22 to be inserted. It will therefore be clear that the objects recited in the preamble to this specification can be amply achieved by this invention.

Having described the invention, what is claimed as new is:

1. A heel having a heel lift, a top lift portion fixed thereto and having a semi-circular recess

at the rear of the top lift portion, a circular disk disposed coaxially of and partially within said recess and having a thickness equal to said top lift portion and a diameter equal to the width of said top lift portion, a plurality of internally threaded thimbles fixed transversely on said heel lift in regular spaced relation near the circumference of the disk, a similar thimble secured transversely of the heel lift coaxially of the disk, and headed screws inserted through said disk into each of said thimbles.

2. A heel having a heel lift, a top lift portion fixed thereto and having a semi-circular recess at the rear of the top lift portion, a circular disk disposed coaxially of and partially within said recess and having a thickness equal to said top lift portion and a diameter equal to the width of said top lift portion, a plurality of internally threaded thimbles fixed transversely on said heel lift in regular spaced relation near the circumference of the disk, a similar thimble secured transversely of the heel lift coaxially of the disk, and headed screws inserted through said disk into each of said thimbles, said disk having reinforcing members embedded therein and apertured to receive said screws.

3. A heel according to claim 2 and wherein said reinforcing members are plates comprising abutment members for the heads of said screws.

HARRY CAMERON.
